MANIFOLDING MACHINE

William G. Borchers, Hoboken, N. J., assignor to
 Autographic Register Company, Hoboken, N. J.,
 a corporation of New Jersey

Application October 28, 1937, Serial No. 171,406

7 Claims. (Cl. 282—12)

The invention relates to manifolding machines and more particularly to a means for protecting worksheet strips having cut-out portions therein while moving to writing position.

5 In using the type of manifolding material wherein the worksheets have cut-out portions in the present manifolding machines, difficulty has been encountered in feeding the strips to writing position due to the contacting of parts of the 10 machine with the edges of the cut-out portions of the worksheets which causes them to buckle and jam and obstruct the free passage of the strips through the machine. This requires that the manifolding machine be opened and the paper straightened out so that it will feed freely through the machine.

15 The device of the present invention avoids these difficulties by providing a means which is secured to the guide rods and which covers the 20 cut-out portion of the worksheets and extends over the end of the platen to protect the worksheet strips in their passage thereto so that they can be freely moved into the writing position without contact with any part of the machine 25 upon which they can be jammed, as for example, the anchoring means for the transfer sheets which extend over the platen in writing position and which are interleaved with the worksheets when they are moved into writing position.

30 The means, according to the present invention, for protecting the cut-out portions of the worksheet comprises flexible strips carried on the guide rods upon which the guide rollers for the several worksheet strips are rotatably mounted. 35 The flexible strips are of a width sufficient to cover the cut-out portion and are adapted to be interleaved with the worksheets so as to protect the cut-out portions in their passage to writing position from contact with any part of the machine. By making the protecting strips relatively narrow, the usual tension means for the strip can be applied to engage the strip at a point spaced from the protecting strips to apply the required tension to the worksheet strips.

40 One of the features of the present invention resides in the provision of a breaker plate which engages the worksheets as they move from the pack so as to spread the nested zigzag folded sheets. In this manner the feeding of adjacent 45 forms through face-to-face contact with one another, which will draw one of the sheets away from its guiding roller, is effectively prevented.

45 Other features and advantages of the invention will be apparent from the specification taken 50 in connection with the drawings, in which:

Figure 1 is a plan view of the manifolding machine partly in section.

Fig. 2 is a longitudinal section of the machine taken along line 2—2 of Fig. 1.

Fig. 3 is a detailed sectional view of the guiding part of the machine showing the guiding and protecting elements in place.

Fig. 4 is a perspective view of the machine showing the arrangement of the guide rollers and the protecting means.

Fig. 5 is a modified form of anchoring means for the flexible strips.

The manifolding machine of the present invention comprises the usual casing 10 which is divided into a supply compartment 11 adapted to hold the package of zigzag folded work-sheets and a storage compartment 12 adapted to receive and store the record sheets. Interposed between the two compartments is the usual feeding mechanism 13, positioned adjacent the forward end of 20 a platen 14 which extends over the supply compartment 11. The feed mechanism is of the usual design and feeds the strips through the machine as desired. The storage compartment is closed by a cover 15 pivoted to the front of the 25 casing and the supply compartment is closed by a cover 16 pivoted to the rear wall of the casing and is provided with an opening 17 positioned over the platen to form the writing opening 30 may be used in the usual manner.

The platen has a plurality of transfer sheets 18, each provided with an anchoring bar 19, which are secured to a pair of anchoring hooks 20 mounted on the platen. The anchoring bars for 35 the transfer sheets are positioned to extend transversely of the machine at the introductory end of the platen and are interleaved with the worksheets 21 as they lie upon the platen to form the manifolding pack. A plurality of guides, one for each worksheet strip, are secured to the back end of the platen. Each guide comprises a guide rod 23 extending across the back of the machine and supported in a pair of brackets 24 secured to the platen. A roller 25, formed of rubber or the like having a metal bushing 25a, is positioned on the guide rod so as to be freely rotatable thereon and is adapted to guide and assist the paper in feeding toward the platen. This can be very clearly seen in Fig. 3.

In using manifolding material of the type wherein openings are formed in the worksheets, difficulty has been encountered in properly feeding the workstrips into writing position due to the fact that the edges of the cut-out portions 50

catch on projecting parts of the machine and cause the paper to jam therein.

In the herein disclosed form of manifolding material, the worksheet is provided with notches 5 cut in the marginal edges thereof at form-length intervals. It is readily understood, however, that these cut-out portions can be positioned throughout the sheet as desired. In order to prevent the cut-out portions from being jammed 10 in the margin, protecting means are provided for covering these openings.

According to the present invention, each of the protective means comprises a plurality of strips 26 of flexible material looped about the guide 15 rods and secured thereto with the free ends thereof extending over the worksheet-receiving end of the platen. These strips are sufficient 20 in width to cover the openings in the worksheets. They extend from the guide rods onto the platen 25 as is clearly seen in Fig. 3, and will protect the strip from catching on the anchoring bars so that the worksheet has a smooth passage into writing position. These flexible strips may be of any material, either metal or fabric, but in the preferred form of the invention they are made of a smooth material having a surface similar to that of tracing cloth. The flexible strips are, according to one form of the invention, secured 30 to the guide rod by means of a staple 27 as shown in Figs. 3 and 4.

In order to properly tension the material moving into writing position, a tension element 28 of resilient material is mounted on the cover and is adapted to engage the worksheet at a 35 point spaced from the protecting means to apply the required tension to the strips in order to hold them securely in writing position.

In order to prevent one sheet from feeding 40 an adjacent sheet and causing the same to be moved away from the guide roller over which it should pass due to the compacting together of the sheets in nested relation when assembled in the zigzag pack, a breaker strip or plate 29 is mounted on the back end of the casing to extend 45 below the guide rollers and horizontally thereof into the supply compartment so as to partially cover the folded pack and to engage the paper in its movement to the guide rollers. This breaker strip comprises an L-shaped metallic member having a smooth rounded end 50 adapted to engage the worksheets. The other end is pivoted on the same hinge as is used by the cover 16 so that it can be moved out of its position over the pack in the storage compartment when it is desired to replenish the pack.

In another form of the invention, shown in Fig. 5, a flexible strip 33 is secured to a guide rod 34 having a guide roller 35. The guide roller, as previously described, is formed of rubber and 60 has a metal bushing 35a therein and is freely rotatable thereon by means of a spring clamp 36 which extends around the guide rod and holds the flexible strip in position by clamping it to the guide rod.

65 In order to adapt the invention so that it can be used with sheets having cut-out portions other than those formed in the longitudinal margins thereof, it is merely necessary to secure the protecting strips on the guide rod so that 70 they will extend over the area of the worksheet including the openings and space the guide rollers to support the strip intermediate the protecting means.

75 Variations and modifications may be made within the scope of this invention and portions

of the improvements may be used without others.

I claim:

1. In a manifolding machine having a platen over which a pile of worksheets having cut-out portions in the marginal edges thereof is fed from a supply compartment; guide rods in the path of the worksheets between the supply compartment and the platen and over which said worksheets pass; and fabric strips secured adjacent the ends of the guide rods so as to cover 10 the marginal edges of the worksheets and extending upwardly to a point above the platen, said fabric strips being adapted to be interposed between the pile of worksheets to protect the cut-out edges of the worksheet from contact with 15 the frame of the machine as they pass into the platen.

2. In a manifolding machine having a platen over which a pile of worksheets having cut-out portions therein is fed from a supply compartment; means for guiding the worksheets from the supply compartment to the platen including guide rollers rotatably mounted on guide rods intermediate the ends thereof; means extending over the cut-out portions of the worksheets to 20 guide the sheets to said platen, said means comprising a fabric strip secured to the guide rods and extending over the edge of the platen whereby the cut-out portion is protected from contact 25 with the frame of the machine; and means for securing the fabric strip to the guide rod.

3. In a manifolding machine having a platen over which a pile of worksheets having cut-out portions in the marginal edges thereof is fed from a supply compartment; a plurality of transfer sheets disposed above the platen and adapted to be interleaved with the worksheets; means extending transversely of the platen at the worksheet-receiving end for anchoring the transfer sheets; means for guiding the worksheets from the supply compartment; and means, disposed longitudinally of the platen, secured to the guiding means so as to cover the cut-out portions 40 of the worksheets and extending upwardly to a point above the platen beyond the securing means for the transfer sheets, said means being adapted to be interposed between the pile of worksheets to protect the edges of the cut-out portion from contact with the parts of the machine.

4. In a manifolding machine having a platen over which a pile of worksheets having a portion of their marginal edges cut out is fed from a supply compartment; means including guide rollers rotatably mounted on guide rods for guiding the worksheets from the supply compartment to said platen; means including flexible strips mounted on the guide rods adjacent the ends of the rollers and extending over the edges of the worksheets to guide the sheets to said platen; 60 and means positioned intermediate the marginal edges of the worksheets for applying tension to the worksheets.

5. In a manifolding machine having a platen over which a pile of worksheets having cut-out portions therein is fed from a supply compartment; a plurality of transfer sheets disposed above the platen and adapted to be interleaved with the worksheets; means extending transversely of the platen at the worksheet-receiving end for anchoring the transfer sheets; guide rods having rollers rotatable thereon mounted in the path of the worksheets between the supply compartment and the platen and over which said worksheets pass; flexible strips secured to the 70 75

- guide rods so as to cover the edges of the worksheets and extending upwardly to a point above the platen beyond the anchoring means for the transfer sheets, said flexible strips being adapted 5 to be interposed between the pile of worksheets to protect the edges of the cut-out portions from contact with parts of the machine; and tension means adapted to engage the worksheets between the marginal edges thereof and spaced 10 from the flexible strips.
6. In a manifolding machine having a supply compartment for the reception of a manifolding pack consisting of zigzag folded forms; a platen over which a pile of worksheets is fed from said 15 supply compartment; a plurality of guides, one for each worksheet, positioned in the path of the worksheets between the supply compartment and the platen and over which said worksheets pass; and pivotally mounted means in the sup-

ply compartment adapted to partially extend over the pack to engage the sheets in their movement to the guiding means to cause the worksheets to be separated from their nested relation.

7. In a manifolding machine having a supply compartment for the reception of a manifolding pack consisting of zigzag folded forms; a platen over which a pile of worksheets is fed from said supply compartment; a plurality of guides, one for each worksheet, positioned in the path of the 10 worksheets between the supply compartment and the platen and over which said worksheets pass; and a breaker plate in the supply compartment adapted to partially extend over the pack and having a smooth edge to engage the sheets in 15 their movement to the guiding means to cause the worksheets to be separated from their nested relation.

WILLIAM G. BORCHERS.
